UNITED STATES PATENT OFFICE.

ROY E. THOMPSON, OF SEATTLE, WASHINGTON.

AUTOMATIC TRAIN-CONTROLLING AND CAB SIGNALING SYSTEM.

1,185,958.

Specification of Letters Patent. Patented June 6, 1916.

Application filed January 2, 1914. Serial No. 810,048.

To all whom it may concern:

Be it known that I, ROY E. THOMPSON, citizen of the United States, residing at Seattle, in the county of King and State of Washington, have invented a certain new and useful Improvement in Automatic Train-Controlling and Cab Signaling Systems, of which the following is a specification.

10 My invention relates to railway block systems of inter-related electrical and mechanical devices which automatically will safely arrest the progress of railway trains when such trains in their operation arrive 15 at a danger zone, and the object of my invention is to provide a block system of automatic signaling and controlling devices that may be associated with a railroad and the locomotives thereof, whereby a signaling device and a train stopping device disposed on 20 the locomotive may be adapted automatically and effectually to operate as follows: First, to control signals for indicating the condition of a block, or blocks, about to be 25 entered by a train. Second, to control the operation of a train stopping device and to prevent the release of such train stopping device after its application has been made, until the train has been brought to a full 30 stop. Third, to provide means whereby, when a train-stopping device has operated and has caused a train to stop, the engineer again causes the train to proceed at a speed less than a predetermined number of miles 35 per hour, as for instance, six miles per hour. Fourth, to display a caution or danger signal and to actuate a train-stopping device upon the removal, breaking or failure, of any essential part of the system, or, upon 40 the occurrence of a break, cross or ground, or the lack of current in any of the electric circuits of the system. Fifth, to display a definite and positive signal for the engineer to proceed at all times when no condition of 45 danger exists, and to display a danger signal or cause a train-stopping device to operate, or both, at any time that a danger condition may arise. Sixth, to provide 50 means for indicating to the engineer of a train the condition of the second block ahead, as well as the condition of a block next ahead, of a train. Seventh, to provide means for causing a train to be brought to 55 a stop and for permitting such train then to proceed at a reduced speed at points where a reduction is deemed advisable for the safe

operation of the train. Eighth, to prevent the immediate operation of a train-stopping device, or danger signal, due to temporary or abnormal short interruption of the current controlling such devices, and to provide means for predetermining the distance that a train may proceed after an interruption of such current, before the effect of such interruption may be transmitted to the train stopping or danger-signaling devices. Ninth, to provide means whereby train-stopping, or signaling devices may be maintained inoperative by the use of a current of relatively low potential between the track 70 rails and the third rail conductor, associated with such train-stopping, or signaling devices, thus avoiding the necessity for better insulation than that ordinarily afforded by the ties, or supports, of such rails 75 and third rail conductor. Tenth, to provide means whereby a current of a proper polarity may be supplied to the train-stopping, or signaling devices of a train through the rails and third rail conductor of a block 80 occupied by such train when no danger exists ahead, and to prevent current being supplied to blocks not associated with a block containing a train or other source of danger, 85 for the purpose of conserving the energy supply against leakage of current due to poor insulation. Eleventh, to provide means for registering the time and duration of the 90 operation of a train-stopping or danger-signaling device. I accomplish and attain these 95 results by devices illustrated in the accompanying drawings wherein—

Figure 1 diagrammatically illustrates my invention as applied to several consecutive blocks of a railroad whereon trains are to 95 travel in one direction only, as on one of the tracks of a double-track railway. Fig. 2 diagrammatically illustrates my invention as applied to several blocks of a railroad track whereon trains are operated to run in 100 both directions, as on a railway that has a single line of railway tracks, and Fig. 3 diagrammatically illustrates the signaling devices and the train-stopping devices, as applied to a locomotive and as electrically associated with the railroad tracks. 105

Like reference numerals may indicate different parts in different figures of the drawings.

Referring to Fig. 1, the numerals 5, 6, 7, 110 8, and 9, respectively, indicate the two rails of consecutive different blocks of a railroad

track, the two rails of each block being insulated from the two rails of the adjacent blocks by insulating members 10, and the two rails of each of the blocks 5, 6, 7, 8 and 9 are each connected with a different terminal of a source of electric current, as with battery cells 11, 12, 13, 14 and 15 respectively.

Adjacent to one of the rails 5, 6, 7, 8 and 9 are disposed electrical conductors, or rails, 16, 17, 18, 19 and 20, respectively, which are insulated from each other by insulating members 21, such rails 16, 17, 18, 19 and 20, comprising a third line of rails, each block of which is adapted to be connected with a source of electric current and is so disposed that an electric contact member extending from a locomotive may continuously engage with such third line of rails.

22, and 22 indicate two of the trucks of the locomotive, as moving in the direction of the arrow, the forward one of such trucks 22 being in contact with the rails 8, while the rearward one is in contact with the rails 7 of the adjacent block, and 23 represents the rearward truck of a locomotive moving in the direction of the arrow and in contact with rails 6, of a block.

Within the locomotive of truck 23 are electric signals 24, and 25 that are adapted to be actuated electrically by batteries 26 and 27, respectively, whose circuits are controlled respectively by a polarized armature 28 and a neutral armature 29, the helices of which armatures 28 and 29 are connected in series in a circuit 30 extending from the truck 23 to an electric contact member 31, which contact member 31 is attached to, and extends from, the locomotive in a position to engage with the third rail conductor 17 as the train moves on the rails 6 of the block. The locomotive of trucks 22, 22 is likewise equipped with signals 32 and 33, and with a polarized armature 34 and with a neutral armature 35 whose respective helices 36 and 37 are connected in series in a circuit 38 which extends between the trucks 22, 22 and the electric contact member 39 of the locomotive, which contact member 39 is disposed to engage with third-rail conductor 19.

Extending throughout the length of the railroad and adjacent thereto are suitably supported insulated main line conductors 40 and 41, respectively, the conductor 40 being connected with one terminal of the battery 42, or with other source of electric current, while the conductor 41 is connected with the other terminal of such source of electrical current.

Adjacent to the forward end of each of the different blocks of the railroad, the forward end portions of the two rails and the third rail conductor are associated with

three electrical circuit switches that are adapted to be actuated by electromagnets as shown in Fig. 1, where an electromagnet 43 is electrically interposed between the end portions of rails 5 to actuate switch arms 44 and 45 to engage with contact points 46 and 47 respectively, and electromagnet 48 is adapted to actuate pole changing switch arms 52 and 53 to control their engagement with contact points 54, 55 and 56, the said switch arms 52 and 53 being connected each to a different one of the terminals of a battery 57, or to another source of electric current, the two terminals 54 and 56 being connected with one of the rails 5 while the terminal 55 is connected with switch arms 49. The forward end of the third rail 16 is connected with the contact point 46 while the contact point 47 is connected to the main line conductor 40 and the switch arm 44 is connected with the contact point 50, the switch arm 45 being connected to a conducting wire 58 which may lead rearwardly to connect with an electromagnet (not shown) which corresponds to the electromagnet 48. The electromagnet 48 has one of its terminals connected to a conductor 59 which may extend rearwardly to connect with an electromagnet, not shown, that corresponds to the electromagnet 51, while the other terminal of such electromagnet 48 is connected to a conductor 60 which extends forward to a switch arm 61 of a group of switches associated with the forward end of the block embodying the rails 6 and the third rail conductor 17. The electromagnet 51 has one of its terminals connected with the main conductor 41 while its other terminal is connected with a conductor 62 that extends forward to connect with an electromagnet 63 of the group of switches associated with the forward end of said block which embodies rails 6 and the third rail conductor 17. The electromagnets 63, 64 and 65 of the forward ends of blocks embodying rails 6, 7 and 8, respectively, correspond to electromagnet 48 in operation and purpose, while electromagnets 66, 67 and 68 similarly correspond to electromagnet 43 and electromagnets 59, 70 and 71 and likewise correspond to electromagnet 51 in function and operation. Electric batteries 72, 73 and 74 in function correspond to the battery 57. The switch arms 75, 76 and 77 correspond to the switch arm 44, while the switch arms 61, 78 and 79 correspond, each, to the switch arm 45. The contact points associated with the switch arms, 75, 61 and 76, 78, 77, and 79, respectively correspond in function to contact points 46 and 47. The switch arms 80, 81 and 82 each with its associated contact point correspond in function with the switch arm 49 and the contact point 50. The pole changing switch arms 83 and 84, 85 and 86, and

87 and 88, respectively, together with their associated contact points correspond in function and operation to the switch arms 52 and 53 and the contact points 54, 55 and 56.

5 Upon tracing the circuit connections, as diagrammatically shown in Fig. 1, it will be seen that when the truck of a locomotive enters a block then the battery, as battery 12, connected between the rails 6, is short circuited through such truck, as truck 23, whereupon the electromagnet which is connected between the rails of that block, as electromagnet 66, will cease to be energized and its switch arms 75 and 61, are drawn 10 back by a spiral spring, as spiral spring 89, to disconnect the switch arm 61 from the main line conductor 40 and at the same time connecting the switch arm 75 with the third rail conductor 17. But if there 15 be no locomotive truck present on a block, as illustrated by the rearward-most block containing rails 5 and third rail conductor 16 together with the battery 11 extending between said rails 5, then in such case, the 20 battery 11 is not short circuited, and being located at the rearward end of the block its current traverses the rails 5 to the forward end of the block thence through the electromagnet 43, to energize it, where- 25 upon the arms 44 and 45 are actuated to disconnect the arm 44 from the third rail conductor 16 and at the same time connect the arm 45 with the main line conductor 40, and a like condition would exist with 30 35 the group of switches associated with the forward ends of the rails 9 and rails of other blocks ahead, not shown, if there be no train on such rails, and the electromagnets, of such groups of switches, which correspond to the electromagnet 43 would be energized to actuate switch arms corresponding to switch arms 44 and 45, with the result that a current from the main line conductor 40 would find a path through an 40 45 electromagnet that corresponds to the electromagnet 65, which electromagnet is associated with the forward ends of the block containing the rails 8, and also to energize the electromagnet 70 that is associated with the forward end of the block containing the rails 7, with the result that the switch arm 82 would engage with its contact point so that the current from battery 74 would find 50 55 60 65 70 75 80 85 88 90 95 100 105 110 115 120 125 130 135 140 145 150 155 160 165 170 175 180 185 190 195 200 Fig. 2 illustrates diagrammatically a railroad having only one trackway upon which trains are operated in both directions. Each of the pairs of rails 4, 5, 6, 7 and 8, respectively, represent a block, adjacent pairs of rails of which are insulated from each other by insulating members 9. As shown, the truck 120 of a locomotive is indicated by an arrow as moving in a direction to the right on the rails of block 5, while a truck 121 of another locomotive is indicated by another arrow as moving in a direction to the left on the rails of block 7, and upon the locomotive of the truck 120 are disposed controlling mechanisms of which polarized electromagnets 18, by their operation, serve to control a signal 14, while an electromagnet 19 by its operation serves to control a signal 15, or, a train-stopping device, while on the locomotive of truck 121 corresponding polarized electromagnets 20 and a corresponding electromagnet 21 are disposed in like manner to control respectively the signal 16 and the signal 17; and like the signal 15 of the locomotive of truck 120, the signal 17 may be replaced by a train-stopping device, or other train-controlling mechanism. Between the rails of each of the blocks, 4, 5, 6, 7 and 8, is disposed a generator of electricity, as the several cells 10, 11, 12 and 13, any of which will be short circuited when the truck of a train rests upon the rails with which it is connected.

Disposed alongside the several blocks comprising the railroad is an electrical conductor, or third rail, divided into insulated sections corresponding to the several blocks 4, 5, 6, 7 and 8, (as the sections 34, 35, 36, 37 and 38 of the third rail conductor shown in Fig. 2) and upon the locomotive of truck 120 is a pole changing device having switch arms 30 and 32 the switch arm 32 being connected electrically with a contact device 28 which may be disposed to extend downwardly from the locomotive continuously to engage and form a contact with the section 35 of the third rail conductor, and upon the locomotive of truck 121 is a like pole changing switch having corresponding switch arms 31 and 33, the switch arm 33 being electrically connected with a contact device 29 which in function and operation corresponds to the contact device 28.

Associated with the switch arms 30 and 32 are the different terminal contact points of a circuit 22 within which circuit 22 are included the polarized electromagnets 18 and the neutral electromagnet 19, and the operation of said switch arms 30 and 32 may cause a change in the polarity of a current present at any time in the circuit 22 and similarly the switch arms 31 and 33 of the locomotive of truck 121 may operate to change the polarity of current present in circuit 23.

Either of the electromagnets 19 and 21 will actuate the respective levers 25 and 27 in response to a current of either polarity in their respective circuits 22 and 23; and contact levers 24 and 25 respectively, of the polarized electromagnets 18 and 20, are adapted by a retractile spring normally to maintain the circuits of signals 14 and 15 respectively, open, when no current is passing in the respective circuits 22 and 23 whereby the signals 14 and 16 would indicate danger, and current of a particular polarity in either of the circuits 22 and 23 will cause its respective circuit of signals 14 or 16 to be open while a current of a different polarity in either of the circuits 22 and 23 will actuate the respective contact lever 24 or 25 to close the circuit of its respective signal 14 or 16 to indicate no danger.

The switch arm 30 is electrically connected with the truck 120 while the switch arm 31 is correspondingly connected to the truck 121 and the switch arms 32 and 33 are electrically connected with a third rail conductor, as shown, by contact members 28 and 29 respectively, and therefore any electricity flowing between a third rail conductor and a truck, as between section 35 of the third rail conductor and truck 120, may be controlled in its direction or polarity in circuit 22 by the pole-changing switch arms 30 and 32.

Extending along the side of a railroad throughout its length are insulated main line conductors 39 and 40 between which conductors 39 and 40 is interposed a source of electricity as battery 41, and at a point on the side of the railroad adjacent to each of the insulating members 9, or block junctions, there is disposed a group of electromagnetic switching devices, as *w*, *x*, *y*, and *z*, each of which groups is electrically associated by connecting wires with the end of the rails of adjacent blocks of the railroad and with an end of the adjacent third-rail conductor, as the group *w*, is associated, as shown, with the end of the rail of block 4 and 5 and with the end of third rail conductor 35.

Electromagnets 42, 43, 44 and 45 of groups *w*, *x*, *y* and *z*, respectively, are electrically connected between the ends, respectively, of the rails of blocks 4, 5, 6 and 7, and such electromagnets are each normally energized electrically by current from the battery that is interposed between the rails with which it is connected, as for instance, the electromagnet 43 of group *x*, is connected between the right hand ends of rails of block 5; but when a truck of a train or locomotive enters the block to rest upon the rails thereof, the battery interposed between such rails is short-circuited in the manner shown where truck 120 of a locomotive short-circ-

cuits the two rails of block 5 and thus prevents the electromagnet 43 from being energized by the cell 10 of battery connected between the rails of such block 5.

5 In each of the groups *w*, *x*, *y*, and *z*, are two distinct pole-changing switches the contact arms of one of which is connected to the contact points of the other, and such contact arms are actuated, in conjunction 10 with a retractile spring, by electromagnets, as by electromagnets 46 and 50 in group *w*, 47 and 51 in group *x*, 48 and 52 in group *y*, and 49 and 53 in group *z*.

The contact arms, respectively, of the 15 electromagnets 46, 47, 48 and 49 are associated with respective contact points disposed to engage, as required, with their upper ends, which contact points respectively, are in electrical connection with one of the rails of 20 the railroad and with one of the third-rail conductors of their respective blocks, as in the case of, say, the group *w*, the pole-changing contact points of the switch arms of electromagnet 46 are electrically connected 25 with section 35 of the third rail conductor and one of the railroad rails of block 5, as shown, thus the operation of electromagnets 46 in conjunction with a retractile spring may serve to change the polarity of 30 current conducted to said section 35 and the rails of block 5 through the switch arms of such electromagnet 46, while the electromagnet 50 by its operation in conjunction with its retractile spring may serve to change 35 the polarity of current supplied to the switch arms of said electromagnet 46 through the switch arms of said electromagnet 50, such current at required times coming from the respective switch arms of electromagnets 54 40 and 55 with which the respective switch arms of electromagnet 50 are connected, the source of such current being cells comprising battery 82, one terminal of which battery 82 is connected with two contact points which respectively are adapted to 45 be engaged by the switch arms respectively of electromagnets 54 and 55.

The integrity of the circuit within which 50 is included the electromagnet 46 is controlled by an insulated contact member attached to the switch arms of the electromagnet 54 which insulated contact member is adapted to engage with two points to close the circuit of electromagnet 46, while the 55 integrity of the circuit containing the electromagnet 50 is controlled by a similar insulated contact member attached to the switch arm of electromagnet 55 which contact member is adapted to engage with two 60 contact points of the circuit of electromagnet 50 to close such circuit.

The electromagnet 55 is provided with a shunt circuit which may be opened or closed at desired times to short-circuit said electromagnet 55, the integrity of which shunt cir-

cuit may be affected by means of another insulated contact member attached to the lower end of the contact arm of electromagnet 55, which contact member is adapted to engage with two contact points connected 70 with conducting wires, 109, and the integrity of such shunt circuit may also be affected by the operation of a contact arm 70 that is actuated by an electromagnet, said contact arm 70 being adapted to engage with two 75 contact points included in said shunt circuit formed by conductors 109.

In a similar manner and for a similar purpose the electromagnet 54 is provided with a shunt circuit comprising conductors 108 80 whereby said electromagnet 54 may be short-circuited when required not to be energized, the integrity of such shunt circuit being affected in a similar manner as in the case of the shunt circuit of electromagnet 55 by an 85 insulated contact member attached to the lower end of the switch arm of electromagnet 54 which contact member may engage with either of two contact points connected with conductors 108 of said shunt circuit 90 while an insulated portion of the switch arm 70 is adapted to engage with either of two other contact points included in said shunt circuit formed by conductors 108.

The battery 83, electromagnets 56, 57 and 95 63, together with their respective switch arms, contact points and circuit wires of group *x*, the battery 84, electromagnet 58, 59, and 64 with their associated switch arms, contact points and circuit wires of group *y*, 100 and the battery 85, electromagnets 60, 61 and 65, together with their respective switch arms, contact points and circuit wires of group *z*, correspond in mode of operation and purpose to the corresponding devices of 105 group *w*, as described.

The main line conductor 40 is connected with one terminal of the respective electromagnets 55, 57, 59 and 61 of the several groups *w*, *x*, *y* and *z*, the other terminal of 110 electromagnet 55 being connected to the main line conductor 39 through conducting wires 78 in circuit with which conducting wires 78 is interposed electromagnet 58 and switch arm 63, while the other terminal of 115 electromagnet 57 is connected to main line conductor 39 by conducting wire, 80, in circuit with which is interposed electromagnet 64, electromagnet 60 and switch arm 69, and the other terminal of electromagnet 59 is 120 connected to main line conductor 39 by conducting wire 123 through electromagnet 65 and through another electromagnet and another switch arm of another group that is not shown, but which would be adjacent to 125 group *z*, such other electromagnet and such other switch arm corresponding in disposition and function to the electromagnet 60 and the switch 69 respectively, and the other terminal of electromagnet 61 is connected 130

by wire 124 to corresponding apparatus of a corresponding group that would be associated with a second block beyond block 8.

Electric current from main line conductor 39 to main line conductor 40 for actuating electromagnets 46 and 50 of group *w*, electromagnets 47 and 51 of group *x*, electromagnets 48 and 52 of group *y*, and electromagnets 49 and 53 of group *z*, is controlled 10 by the upper and lower insulated contact members of switch arms of electromagnets 54, 55, 56, 57, 58, 59, 60 and 61, as for instance, current for electromagnet 50 is controlled by the upper insulated contact member of the switch arm of electromagnet 55 of group *w*, and by the lower insulated contact member of the switch arm of electromagnet 57 of group *x*, and the current for actuating electromagnet 51 of group *x* is controlled by 15 the upper insulated contact member of the switch arm of electromagnet 57 of group *x* and by the lower insulated contact member of the switch arm of electromagnet 59, of group *y*, and the current for actuating electromagnet 52 of group *y* is controlled by the upper insulated contact member of the switch arm of electromagnet 59 of group *y* and the lower insulated contact member of the switch arm of the electromagnet 61 of 20 group *z*.

The corresponding electromagnets of other groups have their current controlled by like insulated contact members of switch arms of their respective groups in the manner I have described.

It will be observed with respect to the third rail contact member of a locomotive of truck 121, which is indicated by an arrow as moving in a direction toward the left, 40 that its contact with the third rail 37 causes the switch arms to lean to the left to direct current through circuit wires 23 in a particular direction with respect to polarity but if the locomotive should be reversed to 45 travel to the right, then said switch arms 31 and 33 would lean to the right to reverse the polarity of the current in said circuit wires 23, and all of the apparatus shown as being associated with the blocks 4, 5, 6, 7 and 8, 50 and with the locomotives of trucks 120 and 121 is adapted to effect results and purposes as follows: First: As shown, a locomotive is moving toward the right on block 5 and another locomotive is moving toward the left on block 7, while block 6 is clear, then in 55 such case, the signal 14 of the locomotive of block 5, by its danger indication will be interpreted as indicating that there is a danger condition in block 7 while the signal 15 will be interpreted as indicating that block 6 is clear and similarly the signal 16 of the locomotive on block 7 will indicate a danger condition on block 5, while the signal 17 of such locomotive will show that block 6 is clear, 60 but if the locomotive on block 7 should be

reversed to travel to the right in the same direction as the locomotive of block 5 is proceeding, then in such case, owing to the reversal of current in circuit 23 the polarized electromagnet 20 will cause signal 16 to 70 show no danger, but signal 14 on locomotive of block 5 will still indicate that a danger condition exists on block 7, and further, if locomotive of block 5 be reversed in direction, then in such case, the signal 14 thereon 75 would show no danger signal that would be caused by any condition of block 7. Second: If the several blocks 5, 6, 7 and 8 be clear of danger condition and a locomotive be proceeding to the right on block 4, then, in such 80 case, the electromagnet 42 would be short-circuited to cause the switch arm 66 to open the circuit 74 to act on electromagnet 54 to actuate its switch arm to cause associated devices to conduct current of a proper polarity from battery 82 to the third rail 35 and the railroad rails of block 5, so that when such locomotive arrives on the rails of a block 5, current from the section 35 of the third-rail conductor and the railroad rails 90 of block 5, of a proper polarity, will be available properly to operate signals 14 and 15 and after the last truck of such locomotive leaves the rails of block 4, then, by reason of the shunt circuit around the electromagnet 54 being completed by the action of electromagnet 62 on the switch arm 70, the third-rail conductor section 35 and the rails of block 5 will be supplied with current of 95 a proper polarity as long as the locomotive 100 is on such block 5, and then in like manner by the action of the now short-circuited electromagnet 43 of group *x*, the rails and the third-rail conductor section 36 of block 6 next ahead will be supplied with current to 105 operate the locomotive signals when such locomotive arrives on block 6. Third: No current will be supplied to the railroad rails and the third-rail conductor of a block unless a danger condition exists in one of the 110 adjoining blocks, but if a danger condition exists in both of the adjoining blocks then no current will be supplied to such railroad rails and third-rail-conductor of such intermediate block. By the term danger condition, it is to be understood to include a defect in any of the apparatus or circuits associated with a block, the presence of a train upon a block, any obstruction that might 115 serve to short-circuit any of the circuits of a block, or a failure of any source of current associated with the circuits of a block. Fourth: A locomotive traveling on a block causes current of a particular polarity to be 120 supplied to the third-rail conductor and the rails of the block immediately ahead will cause also a current of a different polarity to be supplied to the third-rail conductor and railroad rails of the block immediately 125 ahead of the block upon which the loco- 130

motive is moving, and if for any reason such locomotive be reversed to travel back on to such adjacent rearward block, then in such case, the polarity of the current supplied to 5 the railroad rails and third-rail conductor thereof would be proper for the operation of the signals of the locomotive owing to the reversal of the pole-changing switch associated with the contact member of the locomotive that engages with the third-rail conductor, but if a particular block is being 10 approached by two locomotives traveling in opposite directions, when each of said locomotives enters upon the block adjoining such particular block, then in such case, the 15 effect of one locomotive tends to supply a current of a particular polarity while the effect of the other locomotive tends to supply a current of an opposite polarity to the third-rail conductor and rails of said particular block, with the result that no current is supplied to said third-rail conductor and rails of such particular block.

Referring to the signal device 15 and the 20 corresponding signal device 17 of Fig. 2, such signaling devices may be replaced by electrically operated means adapted to control a train-stopping device as may be clearly understood by reference to Fig. 3 of the drawings, wherein 5, 5 are the two railroad rails of a block while 6 is a third rail conductor corresponding to one of the third-rail conductors 34, 35, 36 and 37, of Fig. 2, and 7 represents the truck of a locomotive 25 resting on said rails 5, 5. A contact member 8, which is shown as being in engagement with the third rail conductor 6, is attached to the lower end of an insulated arm 9 which is secured to a yielding support connected with the locomotive, such insulated arm 9 being adapted to engage with one contact point 10 of a pole-changing device when the locomotive is traveling in one direction, and to engage with a different contact point 40 11 of such pole-changing device when such locomotive is traveling in an opposite direction, and attached to such insulated arm 9 at its upper end is an insulated member 12 that is electrically connected by a conductor 45 13 with the truck 7 of the locomotive and such upper insulated member 12 is adapted to engage with a contact point 14 of said pole-changing device at the same time that the contact point 10 is caused to engage with 50 said insulated arm 9, while a contact point 15 of said pole-changing device is adapted to be engaged with said upper insulated member 12 at the same time that the insulated arm 9 is caused to be engaged with 55 the contact point 11.

The two contact points 10 and 15 are both connected to the terminals 16 and 18 of another pole-changing device, while the contact points 11 and 14 are both connected 60 with terminals 17 and 19 of such other pole-

changing device, as shown, and terminals 20 and 21 are connected to a circuit 22 which includes in series a polarized electromagnet 23 and a solenoid neutral electromagnet 24, said polarized electromagnet 23, in conjunction with a retractile spring 25, is adapted to actuate a contact arm 26, to make and break contact with contact points 27, and such contact arm 26, with its retractile spring 25, is connected to a circuit 28, which 70 circuit 28 includes an electromagnet 29, a battery 30, and the contact point 27, whereby said contact arm 26, by its movement, may open or close such circuit through contact point 27. The electromagnet 29, by a 80 suitable means, is adapted to actuate a signal device 31.

The solenoid electromagnet 24 is pivotally mounted to swing on a pivot 32 in sidewise directions, and is provided with an armature 85 33, adapted to move lengthwise within it so that its lower end may engage with a worm-screw on the axle of the truck 7, as shown, when no current is present in circuit 22, and is further adapted to be raised upwardly to 90 free its lower end from a worm-screw 35, when current is present in circuit 22. Freely mounted upon said armature 33 is an annular contact member 34 that normally is supported by collar 36 which is fastened by a 95 pin on the armature 33 as shown.

On each of opposite sides of the armature 33 is disposed a contact point 37, which contact points 37 are secured to, but insulated from, the respective sides of the solenoid electromagnet 24, and when a current is present in circuit 22 the annular contact member 34 will be raised by the collar 36, upon which it normally rests, to be clear of engagement with contact points 37, but when no current is present in circuit 22, the falling of the armature 33, with its collar 36, permits the annular contact member 34 to move downwardly into engagement with the contact points 37, to rest thereon, while said armature continues to move downwardly to engage its lower end with the worm-screw 35.

At equidistant points on opposite sides of the solenoid magnet 34 are fixed brackets 38 and 39 respectively, to which are swingingly attached insulated contact members 40 and 41 and 42 and 43 respectively, and at the lower end of contact member 41 and at the lower end of contact member 43 is fixed a 115 projecting stud 44, which extends toward the armature 33, and is adapted to be engaged with said armature 33 when said armature 33 is caused by the worm-screw 35 to swing in sidewise directions. Associated with insulated contact member 40 is a pair of contact points 45, and with insulated contact member 41 is associated a pair of contact points 46, at the left of the solenoid magnet 24, while at the right thereof insu- 120 125 130

lated contact member 42 is associated with a pair of contact points 47 and the insulated contact member 43 is associated with a pair of contact points 48, all of which contact points are disposed so that when the worm-screw 35 acts upon the armature 33 to move it in a sidewise direction, one of the studs 44 will be caused to separate the respective insulated contact members from their respectively associated contact points to open the circuits within which such contact points are included.

The lowest one of the pair of contact points 46 and the lowest one of the pair of contact points 48 is electrically connected each with one of the contact points 37 by a flexible conductor, while the upper contact of such pairs of contact points 46 and 48 are connected to the wires comprising circuit 28, within which is included the electromagnet 29 and the battery 30, while the lower contact points of the pairs of contact points 45 and 47 are connected directly together with a connecting wire 49, and the upper one of each of the pairs of contact points 45 and 47 form terminals of a circuit 50 within which is included a battery 51, and a solenoid electromagnet 52, and thus when the armature 33 is drawn to its uppermost position by presence of current in circuit 22, then the insulated contact members 40 and 42 serve to close the circuit 50 by engaging with the pairs of contact points 45 and 47 respectively, whereby the solenoid electromagnet 52 may actuate its armature 53 to control the position of a lever 54, with which it is connected as shown. The lever 54 is provided with an arm 55 which may be connected with any suitable train-stopping device (not shown) as for instance, means for shutting off steam and controlling the flow of steam or of air of braking apparatus, or such lever 54 may control signaling devices as signals 15 and 17 of Fig. 2, and further said lever 54 may be associated with a registering device comprising paper 56, moved by suitable mechanism (not shown) beneath a marking device 57, actuated by said lever 54.

Obviously any form of automatic registering device that is adapted to be electrically controlled may be associated with the circuit 50 so as to indicate when such circuit 50 has no current present in it.

A vertical shaft 58 is suitably mounted to revolve in bearings, (not shown) and on the lower end of such shaft 58 is fixed a beveled gearwheel 59, disposed to engage with a beveled gearwheel 60, that is fixed on the shaft of the truck 7, to revolve with its shaft, while on the upper end of said vertical shaft 58 is fixed a beveled gearwheel 61, adapted to engage with and revolve two gearwheels 62 and 63, one of which gearwheels 62 and 63 is associated with a hori-

zontal shaft 64, by means of a pawl and ratchet mechanism (not shown) to permit such one wheel to rotate freely around said shaft 64 in a particular direction only, while the other of said beveled gearwheels 62 and 63 is associated with said shaft 64 by like pawl and ratchet mechanism (not shown) to permit it to rotate freely around said shaft 64 in an opposite direction only, and upon one end of said horizontal shaft 64 is rigidly mounted a disk 65, upon the periphery of which is formed a ridge, or flange portion 66, which is slotted diagonally to form a slot 67, which extends through it from one side to the other.

A shaft 68 is mounted to revolve in suitable bearings (not shown) and disposed so that its axis is in line with the axis of the shaft 64, one of its ends being adjacent to the disk 65 and such end is provided with a crank arm 69, to the end of which crank arm 69 is secured a flat spring 70, preferably of steel, upon the lower end of which is an engaging member 71, the position of which spring 70 and engaging member 71, with relation to the flange 66, is such that if the shaft 64 is turned in one direction at a greater speed than the shaft 68, then in such case, the engaging member 71 will be caused to engage with one side of the flange 66, as shown by the dotted lines, while if said shaft 64 is turned at a less rate of speed than the shaft 68, then in such case, the engaging member 71 will be caused to engage the opposite side of said flange 66, as shown by the full lines in the drawings. In the shifting of the engaging member 71 from one side to the other of said flange 66, such engaging member 71 passes through the slot 67.

Attached to the crank arm 69 but electrically insulated therefrom is an angular bracket 72 which is provided, near its lower end portion, with an adjustable electrical contact screw 73, whose contact point is adapted to make electrical contact with the spring 70 when said spring 70 is in the position indicated by full lines and is further adapted to break such contact when said spring 70 is in position indicated by dotted lines. The bracket 72 is electrically connected by conductor 74 with an electrically insulated contact wheel 75, that is mounted on the shaft 68 to revolve with it, and connected with said contact wheel 75 is one terminal of a circuit 76, while the shaft 68 is connected with the other terminal of such circuit 76, said circuit 76 being connected with circuit 50 in shunt with electromagnet 52 and battery 51.

The circuit 76 is adopted to be opened and closed by a circuit breaker comprising a contact arm 77, and a contact point 78, in the operation of which said contact arm 77 is actuated by a retractile spring 79, and

an electromagnet 80, which said electromagnet 80 is included in said circuit 76, together with the contact arm 77 and the contact point 78, which contact arm 77 and contact point 78 may be shunted by a circuit 81 that is controlled by a contact point 83 and spring contact member 82 included therein, said contact member 82 being actuated in response to the operation of a lever 84 when such lever 84 is operated to reverse the direction of the locomotive, the operation and function of such lever 84 and its associated parts being well understood by locomotive engineers.

15 The mechanisms and circuits associated with the locomotive and the rails of a railroad together with a third-rail conductor, as diagrammatically illustrated in Fig. 3 of the drawings, and as described above, are adapted to operate as follows: The shaft 68 is caused to revolve continuously by a power communicated from an independent source (not shown) at such a predetermined and constant rate of speed as will cause the engaging member 71 to close the circuit 76 between the spring 70 and the contact point 73, so long only as the rate of speed of the locomotive shall cause the shaft 64 to revolve at any rate of speed less than the rate of speed of the shaft 68. For instance, if it be desired that circuit 76 shall be closed at all times when the locomotive is traveling at any speed less than six miles per hour, then the predetermined rate of rotation of the shaft 68 shall be such as will be greater than the rate of rotation of the shaft 64 will be when the locomotive is traveling at six miles or less per hour, and then in such case if the locomotive exceeds a speed of six miles per hour, the shaft 68 will be rotating more slowly than shaft 64, whereupon the engaging member 71 will be caused to pass through the slot 67, to the other side of the flange 66, and the circuit 76 will be opened.

20 30 35 40 45

The purpose of having the circuit 76 closed at all times while the locomotive is traveling at less than a particular rate of speed, say six miles per hour, is to form a shunt around the solenoid electromagnet 52 and the battery 51 so that such solenoid electromagnet 52 may be energized irrespective of the conditions of the circuit controlling mechanisms associated with the circuit 50, whereby the solenoid electromagnet 52 will be energized to prevent the operation of the train-stopping device in spite of any operation of the solenoid electromagnet 24, and its associated mechanisms, which otherwise might cause the solenoid electromagnet 52 to be deenergized to permit the train-stopping mechanism to operate to stop the train. If, when the locomotive is proceeding at more than say, six miles per hour, then if the locomotive arrives on a danger zone, the sole-

25 30 35 40 45 50 55 60 65

noid electromagnet 24, and its associated mechanisms, will cause the solenoid electromagnet 52 to be deenergized to permit the train-stopping device to bring the locomotive to a full stop, whereupon the engaging member 71 will then be disposed upon the left hand side of the flange 66 to close the circuit 76 between the spring 70 and the contact point 73, but such circuit 76 will be open between contact point 78 and contact lever 77 and the shunt circuit 81, which shunts the contact lever 77 and the contact point 78 will be open between the contact point 83 and the spring 82; then in order to cause the locomotive to start, the engineer will throw the reversing lever 84 first backwardly, and then forwardly again, whereby such lever 84 is caused to actuate the spring 82, momentarily to close the shunt circuit 81, by making it engage with contact 83, with the result that the electromagnet 80 will cause the contact lever 77 to engage with contact point 78 and to maintain such contact to close the circuit 76, whereupon the battery 51 will be permitted to send current 90 through solenoid electromagnet 52 to raise the lever 54, whereby the effect of the train-stopping device will be removed, and the train may proceed in the danger zone at a speed of less than six miles per hour, but if the locomotive should proceed at a greater rate of speed than six miles per hour while the danger conditions still exist, then the circuit 76 would be opened between the spring 70 and the contact point 73, again to 95 deenergize the solenoid electromagnet 52, thus again to bring the train-stopping device into operation; if, however, the danger condition in the meantime be removed, then in such case, whether the circuit 76 be opened 100 or closed, the circuit 50 will be closed by the operation of the solenoid electromagnet 24, and its associated mechanisms whereby the solenoid electromagnet 52 would be energized to prevent the operation of the train- 105 stopping device.

110

The automatic registering device comprising the moving paper 56 and the marking device 57, in a manner obvious to those skilled in the art, will serve to register the 115 time and duration of the action of the train-stopping device in response to movements of the lever 54 which lever 54 is moved upwardly by the action of armature 53 against the force of gravity of the weight on such lever 54.

The different sets of contact points and contact members which are associated with the solenoid electromagnet 24, and which control the integrity of circuits 28 and 50, are controlled by the sidewise swinging movements of the solenoid electromagnet 24, with its armature 33, which sidewise movements are produced by the conjoint action of the armature 33 and the worm-screw 35, 125 130 135

such sidewise movement in either direction corresponding to the direction of rotation of the axle of truck 7, thus, when the solenoid electromagnet 24 is deenergized, its 5 armature 33 drops into engagement with the worm-screw 35 and is thereby gradually moved in one direction or the other, according to the direction of rotation of the axle of truck 7. Thus the axle of truck 7 may 10 make a number of revolutions before the armature 33 engages with either of the studs 44, to cause any of the contact members to move, whereby if the current in circuit 22 is only momentarily interrupted, or changed 15 in polarity, such momentary interruption or such change in polarity of such current in circuit 22, will not affect the integrity of any of the circuits controlled by the contact points and contact members associated with 20 said solenoid electromagnet 24, since the number of revolutions of the axle of truck 7 and worm-screw 35, required to move the armature 33 into engagement with a stud 44, will not have taken place unless the locomotive 25 moves over a predetermined distance and the interruption continues to exist after the locomotive has moved over such predetermined distance. Whenever an interruption ceases to exist, should it be before, or 30 after, the locomotive has proceeded over such predetermined distance, then the solenoid electromagnet 24 would immediately raise the armature 33 from the worm-screw 35, again to assume its normal midway position 35 between the studs 44.

The circuit 22, within which is included the helices of the solenoid electromagnet 24 and the polarized electromagnet 23, is adapted to be supplied with current due to 40 the difference in potential between the third rail conductor 6 and the rails 5, such current traversing an automatic pole-changing switch comprising the insulated contact members 9 and 12, and the contact points 10 and 14 and 11 and 15, and further traversing a manually operated pole-changing switch comprising in part, contact terminals 16 and 17, and 18 and 19, together with terminals 20 and 21, the first named of which pole-changing switches is associated with the contact device 8, that is adapted to engage with the third-rail conductor 6, while the last named of such pole-changing switches is disposed on the locomotive, to be accessible 50 to hand of the engineer.

The polarized electromagnet 23, in response to a current of a particular polarity in circuit 22, causes the contact arm 26 to engage with the contact point 27, in spite of 60 the retractile force of the spring 25, while an opposite polarity of such current, or a cessation of such current, will separate the contact between said contact arm 26 and the contact point 27, thus to control a shunt 65 circuit across the circuit 28, within which is

included a battery 30 and the electromagnet 29, which electromagnet 29 controls the signal 31, and the solenoid electromagnet 24 (included within said circuit 22) responds to a current of either polarity in said circuit 22. 70

When no condition of danger exists in either of the two blocks next ahead of the locomotive with respect to the direction of travel, then a particular polarity of the current in circuit 22 will cause the shunt circuit containing the retractile spring 25, the contact arm 26, and the contact point 27, normally to be closed, whereby the signal 31 will show no danger, the circuit 28 being 80 normally open by reason of the position of armature 33 which armature 33 raises the collar 34 from contact points 37, but if a danger condition be present in either of the two blocks next ahead of the locomotive, the 85 contact between contact arm 26 and the contact point 27 will be open, to cause signal 31 to show danger due to the cessation, or reversal, of the current in circuit 22. If the danger condition has caused a cessation of 90 current in circuit 22, while the contacts 26 and 27 would be open and the circuit 28 would be closed (by the collar 34 dropping upon contact 37, due to solenoid electromagnet 24 being deenergized, permitting the 95 armature 33 to drop into engagement with worm-screw 35) such circuit 28 will again be opened by reason of the sidewise movement of the armature 33 against one of the studs 44, thus opening circuit 28 after the 100 locomotive has proceeded for a predetermined distance. In case the current in circuit 22 is merely reversed in polarity by a danger condition ahead of the locomotive, then the contact arm 26 would be moved by 105 the retractile spring 25 with the aid of the polarized electromagnet 23 to disengage with the contact point 27, to open the circuit 28, to cause the signal 31 to show danger, even though such circuit 28 would be 110 momentarily closed by the collar 34 dropping for an instant onto contact points 37.

The function of the manually operated pole-changing switch is that the engineer may reverse the polarity of the current in 115 circuit 22 in case he desires to reverse the direction of travel of the locomotive, the reversal of direction of which locomotive would cause the automatic pole-changer that is associated with contact member 8, to 120 change the current of such circuit 22, to a polarity that would cause the signal 31 to show a condition of danger existing two blocks in the rear instead of in the now forward direction, unless the manually operated pole-changer be also reversed. 125

What I claim is:

1. In an automatic train controlling and cab signaling system, a railroad whose two rails are divided into blocks of a desired 130

length; the two rails of each block being insulated from the corresponding rails of adjacent blocks, a source of electricity connected between the end portions of the two rails 5 at one end of each of said blocks, a sectional insulated electrical conductor disposed adjacent to one of the rails of each of said blocks to extend throughout the length thereof, electromagnetic switches whose electromagnets 10 are each connected in a circuit extending between the end portions of the two rails at the other end of each of said blocks, a source of electricity disposed adjacent to such other end of each of said blocks, an 15 electrical circuit connected with and extending from said latter source of electricity of each block to connect with said insulated electrical conductor and with one of said rails, a system of electromagnetically operated 20 switches adapted to control the flow of electric current in said electric circuit of each block in response to the operation of the said electromagnetic switches that are associated with the rails of the adjacent 25 blocks and with the block next beyond each of said adjacent blocks, and a source of electricity connected between one of the contact points of each of said electromagnetic switches and one of the terminals of one of 30 the magnets of the respective one of said systems of electromagnetically operated switches, the operation of such one of said magnets being controlled by the operation of that one of said electromagnetic switches 35 which is in the block next beyond the adjacent block.

2. In an automatic train controlling and cab signaling system, a railroad whose two rails are divided into insulated blocks of desired 40 lengths, a source of electricity connected between the two rails of each of said blocks at one end thereof, the electromagnet of an electromagnetic switch connected between said two rails of each of said blocks at 45 the other end thereof; a sectional insulated electrical conductor disposed adjacent to and parallel with one of the said two rails of each of said blocks; an electric circuit for each block connected between said insulated conductor and its adjacent rail, said circuit including a system of electromagnetically 50 actuated pole-changing switches; an electric generator for energizing said circuit of each block with a current of required polarity in response to the operation of said system of 55 said pole-changing switches; a circuit connecting said electromagnetic switch of each block with its system of pole-changing switches and with the corresponding system 60 of the first and second blocks next adjacent to one end of such block whereby the operation of one of said electromagnetic switches due to the short circuiting of the two rails of one of said two adjacent blocks shall cause 65 said systems of pole-changing switches to

operate to change the polarity of the current in said conductor and said rail of their respective blocks; a locomotive adapted to travel successively over the rails of said blocks; an electric circuit associated with 70 said locomotive, one terminal of which is connected with the wheel of said locomotive, while the other terminal is provided with electrical contact means adapted to engage with said adjacent insulated conductor; a 75 polarized electromagnet and a neutral electromagnet connected in series in said circuit; a signal adapted to be actuated by said polarized electromagnet in response to a change of polarity of an electric current in 80 said circuit; and another signal adapted to be actuated by said neutral electromagnet in response to a current in said circuit.

3. In an automatic train controlling and cab signaling system for a single track railway, a railroad whose two rails are divided into blocks of a desired length, the two rails of each block being insulated from the corresponding rails of adjacent blocks, means connected between one of the end portions 85 of the two rails of each block whereby a difference in an electrical potential may be created between two such rails, an electromagnet connected in a circuit extending between the other end portions of the 90 two rails of each of said blocks, an insulated electrical conductor disposed adjacent to one of the rails of each of said blocks to extend throughout the length thereof, a source of electric current disposed near said other end 95 portions of said two rails of each of said blocks, an electric circuit connecting said source of electric current with said insulated conductor and one of said rails of its respective block, two electromagnetically operated 100 pole-changing switches connected in series with each other and with said source of electric current in said electric circuit, means associated with said pole-changing switches and with the track circuits of the second 105 block ahead and the adjacent rear block whereby said one of said pole-changing switches may respond to changes in condition of said second block ahead while the other of said pole-changing switches may 110 respond to changes in conditions of said adjacent rear block.

4. In an automatic train controlling and cab signaling system for a single track railway, a railroad whose two rails are divided 115 into blocks of a desired length, the two rails of each block being insulated from the corresponding rails of adjacent blocks, means connected between one of the end portions 120 of the two rails of each block whereby a difference in an electrical potential may be created between such two rails, an electromagnet connected in a circuit extending between the other end portions of the two rails of each of said blocks, a sectional insulated 125

- electrical conductor disposed adjacent to one of the rails of each of said blocks to extend throughout the length thereof, a source of electric current disposed near said other end 5 portions of said two rails of each of said blocks, an electric circuit connecting said source of electric current with said insulated conductor and one of said rails of its respective block, two electromagnetically operated 10 pole-changing switches connected in series with each other and with said source of electric current in said electric circuit, means associated with said pole-changing switches and with the track circuits of the second 15 block ahead and the adjacent rear block whereby said one of said pole-changing switches may respond to changes in conditions of said second block ahead while the other of said pole-changing switches may respond to changes in conditions of said adjacent rear block, a locomotive adapted to travel on said blocks, an electric circuit for connecting said adjacent sectional insulated electric conductor with the wheels of said 20 locomotive, two signaling devices carried by said locomotive, a polarized electromagnet disposed in said last named circuit and adapted to operate one of said signaling devices and a neutral electromagnet disposed 25 also in said last named circuit and adapted to operate the other one of said two signaling devices.
5. In an automatic train controlling and cab signaling system, a railroad whose two 30 rails are divided into insulated blocks of desired lengths, a source of electricity connected between the two rails of each of said blocks at one end thereof, an electromagnetic switch whose electromagnet is connected between said two rails of each of said blocks, an electric circuit for 35 each block connected between said insulated conductor and its adjacent rail, said circuit including a system of electromagnetically actuated pole-changing switches, an electric generator for energizing said circuit of each 40 block with a current of required polarity in response to the operation of said system of said pole-changing switches, and a circuit connecting said electromagnetic switch of each block with its system of pole-changing 45 switches and with the corresponding systems of the first and second blocks next adjacent to one end of such block whereby the operation of one of said electromagnetic switches, due to the short circuiting of the two rails 50 of one of said two adjacent blocks, shall cause said systems of pole-changing switches to operate to change the polarity of the current in said conductor and said rail of their respective blocks.
6. In an automatic train controlling and

cab signaling system for railways, a railroad whose two rails are divided into blocks of desired lengths, the two rails of each block being insulated from the corresponding rails of adjacent blocks, a sectional insulated 70 electrical conductor disposed adjacent to one of the rails of each of said blocks to extend throughout the length thereof, means for creating a difference in electrical potential between the said insulated electrical conductor and one of the rails of each of said blocks, a locomotive adapted to travel on the rails of said blocks, an insulated electrical contact member attached to said locomotive and adapted to engage with said insulated electrical conductor, a conducting circuit extending between said electrical contact member and the wheels of said locomotive, a neutral electromagnet disposed in said circuit, a polarized electromagnet 75 connected in said circuit in series with said neutral electromagnet, a manually operated pole-changing switch included in said circuit, another pole-changing switch included in said circuit and adapted to operate in 80 response to a change in the direction of travel of said locomotive, a signaling device associated with said polarized electromagnet and adapted to be actuated thereby, a train stopping device associated with said 85 locomotive, an electromagnet adapted to control such train stopping device, an electrically energized circuit within which is connected said last named electromagnet, switches associated with said neutral electromagnet, mechanical means associated with said locomotive, said mechanical means being adapted to coact with said neutral electromagnet to control said energized circuit 90 in response to the travel of said locomotive 95 for a predetermined distance, whereby accidental interruption of current between said insulated conductor and said contact member may not actuate said train stopping device within said predetermined distance of 100 travel, an electro-mechanical means associated with said energized circuit whereby said train stopping device may not operate if said locomotive is traveling at a desired 105 minimum rate of speed.

7. An automatic train controlling and cab signaling system embodying a railroad whose two rails are divided into insulated sections of desired lengths; a sectional insulated electrical conductor disposed adjacent to and parallel with one of said two rails of each of said blocks; an electric circuit for each block connected between said sectional insulated conductor and the adjacent rail; an electric generator for energizing 110 said electric circuit of each block; and two electromagnetically actuated switches associated with said electric generator and each of said electric circuits whereby when both of said switches are opened or are 115 120 125 130

closed no current can gain access to said sectional insulated conductor and when a particular one of said switches is open and the other closed then a current of a particular 5 polarity may gain access to said sectional insulated conductor and when said particular one of said switches is closed and the other one is open then a current of an opposite polarity may gain access to said sectional insulated conductor.

8. An automatic train controlling and cab signaling system which embodies a railroad track whose two rails are divided into insulated sections of desired lengths; a sectional insulated electric conductor disposed adjacent to and parallel with one of the said two rails of each of said railroad tracks; an electric circuit disposed in said locomotive; electric signaling devices associated 15 with said circuit in said locomotive; means for electrically energizing said sectional insulated electric conductor and the adjacent rail of said railroad track; a pole-changing switch associated with said electric circuit 20 in said locomotive; and a yielding arm provided with an electric contact disposed to engage with said sectional insulated conductor, said arm being operatively associated 25 with said pole-changing switch in such manner that said pole changing switch shall operate to reverse the polarity of the current flowing therethrough in response to changes 30 in the direction of travel of said locomotive.

35 9. An automatic train controlling and cab

signaling system which embodies a locomotive; an electric signaling device disposed in said locomotive; an electric circuit in which said signaling device is included; a source of electricity for energizing said electric circuit; a circuit breaking switch included in said electric circuit for controlling the operation of said signaling device; and mechanism associated with the running gear of said locomotive and with said circuit breaking switch whereby said circuit breaking switch may be operated in response to an increase of velocity above or below a predetermined velocity of said locomotive.

10. An automatic train controlling and cab signaling system which embodies a locomotive, an electric signaling device disposed in said locomotive; an electric circuit in which said signaling device is included; a generator of electricity included in said circuit; an electric switch for controlling the integrity of said electric circuit; and an electrically controlled mechanism associated with said switch and with one of the axles of said locomotive whereby said switch may 55 be operated in response to a change in the polarity of the current of said electrically controlled mechanism.

In witness whereof, I hereunto subscribe my name this sixth day of December, A. D. 60 1913.

ROY E. THOMPSON.
